ROTARY EXPANSIVE TOOL.

Application filed January 19, 1928. Serial No. 247,824.

This invention has to do with expansive well tools, and, in the typical embodiment here described, with devices of the type generally known as expansive reamers or underreamers, and particularly with rotary underreamers; the particular objects and accomplishments of the invention will perhaps be best understood from the subjoined specific description of a preferred embodiment of the invention; but I may state preliminarily that among the various objects of the invention there is the object of providing a reamer which does not depend upon the action of a spring for its expansion but is expanded by a positive movement, and is likewise contracted by positive movement. Also involved in the invention, and adapted to the particular features of design which embody other characteristics, is the feature of locking the cutters in their inward or contracted positions so that they may be prevented from "riding" the pipe while the reamer is passing through the well pipe. In the characteristic typical design hereinafter explained the structure and operation are such that, when the reamer passes below the well pipe and is to be expanded, positive rotation of the drill stem in a right handed direction causes positive expansion of the reamer. Then when it is desired to contract the reamer it is not necessary to rotate the drill pipe in the opposite direction, or left-handedly, but it is only necessary to pull the reamer up against the bottom of the well pipe or well pipe shoe when it will be immediately contracted. In this contracted position the cutters are held inwardly so that they do not press against the pipe, and the reamer may be withdrawn from the well. Upon subsequent insertion the reamer may be either inserted in its contracted condition in which it has been withdrawn from the well, or it may be placed in what may be termed its normal contracted condition; but as will be noted hereinafter, from either of its contracted conditions the reamer may be thrown to its expanded position by positive right handed rotation of the drill stem.

In the illustrative embodiment of the invention hereinafter described there are many other characteristic features, such as the formation of the cutter carriers, and their engagement and interaction with the expanding cams, etc., but all of which will be best understood when the embodiment is consid-

ered in detail. I refer to the accompanying drawings, in which:

Fig. 1 is an elevation of the present preferred embodiment of the invention showing the reamer contracted; 60

Fig. 2 is an enlarged central longitudinal section also showing the parts in contracted position, this section being taken as indicated by line 2—2 on Fig. 3; 65

Fig. 3 is a cross section on line 3—3 of Fig. 2; 70

Fig. 4 is a cross-section on line 4—4 of Fig. 2; 75

Fig. 5 is a section similar to that of Fig. 2, this section being taken as indicated by line 5—5 on Fig. 6. 80

Fig. 6 is a cross-section on the line indicated 6—6 on Fig. 5; 85

Fig. 7 is a vertical longitudinal section of the parts showing them in the contracted position they assume as they are drawn up through the pipe, this section being taken as indicated by line 7—7 on Fig. 8; 90

Fig. 8 is a cross-section of the reamer taken as indicated by line 8—8 on Fig. 7; and 95

Fig. 9 is a similar cross-section showing the parts in the position which they assume just before going back to the position shown in Figs. 2 and 3. 100

In the drawing there is shown a reamer body 10 which for the purposes of the specific design herein delineated is made up of an upper head 11 and lower head 12 joined together longitudinally by connecting members or webs 13. For purposes of assembling and disassembling the particular design herein shown these webs 13 may be releasably connected with one of the heads, as for instance by the screws or bolts 14, one of which is shown in Fig. 1. The body as thus made up may be either regarded as a sort of cage with upper and lower heads, or may be regarded as a slotted body (the slots lying between adjacent connecting webs 13) with an internal bore (the space inside the webs 13). A mandrel is provided which extends longitudinally through the body, and in this particular embodiment is shown as made up of several interconnected parts. The upper mandrel portion 15 extends through upper head 11 and has at its upper end the usual tapered and threaded pin 16 for connection with a drill stem as shown at 17. The middle mandrel portion 18 is the cam carrying part of the mandrel and it extends vertically between the 110

two heads of the body, being screw-threaded at 19 to the upper mandrel portion. The lower mandrel portion 20 is screw-threaded at 21 to the middle mandrel portion and has at 5 its lower end a screw-threaded box 22 to receive the threaded pin of a drill bit 23. Although I have shown the mandrel thus as made up of three separate parts removably joined together, and although for some reasons it may be desirable to thus construct the 10 mandrel, the mandrel can be made in a single piece; and as in operation it acts as a single member I shall hereinafter refer to this composite mandrel merely as the mandrel except 15 where otherwise specifically stated.

Near its upper end the mandrel passes through a bore 25 in the upper end of upper head 11, in which bore the mandrel is both rotatable and longitudinally movable; and near 20 its lower end the mandrel has the same kind of bearing in the bore 26 of the lower head. A coil spring 27, within upper head 11, normally presses the mandrel down, the lower end of this spring rests upon a mandrel shoulder which may conveniently be formed by a 25 ring or washer 30 which surrounds the mandrel and rests upon the upper faces of the uppermost cam members 32. These cam members are arranged in sets, and of the sets 30 there may be any suitable number, depending upon the number of cutters or cutter sets used in the reamer. In the particular design here shown I utilize three cutter sets and therefore three cutter carriers and three sets of cam 35 members. Likewise each set of cams (each of the vertical rows of cam members 32) may contain any desired number of cam members, depending upon the number of separate cutter carrying arms that is utilized in each cutter 40 carrier. From a consideration of the detailed description of structure and operation which follows it will be readily recognized that my invention may be applied to cutter carriers which embody but a single extending cutter carrying arm—in other words to cutter carriers which are not furcated into a series of vertically spaced arms—or which have the vertically spaced recesses which the 45 spaced arms specifically provide—or, as shown in the drawings, to cutter carriers having any desired number of vertically spaced cutter carrying arms. One advantage in using cutter carriers with a plurality of vertically spaced arms or vertically spaced 50 recesses is, as will be understood from what follows, that the vertical movement of the mandrel and the cam members need not be so large in order to move a cam member vertically from a position where it is behind a cutter carrier or cutter carrying arm to a position where it is above the carrier or carrier arm or in register with a recess. Another advantage of using a cutter carrier divided into a number of vertically spaced arms lies in the 55 fact that a number of separate cutter mem-

bers, such as separate rollers, may be utilized, and the roller mandrel given very solid support at closely spaced points along its length.

Each of the cutter carriers 35, in the specific embodiment shown in the drawings, is here 70 shown as a swinging cutter carrier. It will be recognized that the essential characteristics of the cutter carrier for this reamer require merely that the cutter carriers shall be movable inwardly and outwardly to and from 75 the central axis of the reamer; and, broadly speaking, the cutter carriers can be mounted so as to move in any suitable manner. But for purposes of simplicity of structure and 80 surety of action I choose to mount the cutter carriers pivotally to swing about their axis pins 36 which are located on vertical axis lines near one of the carrier edges. The opposite edge portion of each carrier is divided into a number of vertically spaced arms 40 85 which allow sufficient space between them for the interposition of roller cutters 41 mounted on mandrel pins 42 each of which preferably extends vertically throughout the vertical length of a cutter carrier. Thus in the 90 particular design here shown each mandrel pin 42 carries three roller cutters 41, and each separate roller cutter 41 is thus supported on a mandrel pin which is supported immediately adjacent each roller cutter by an arm of 95 the carrier. And, as will later be seen, as each carrier arm is directly supported from the interior by a cam member, the radial and circumferential thrust support of each roller cutter becomes very strong and direct, all 100 of the parts being put into direct compressive or shearing stress rather than having any bending stresses imposed upon them.

Located within the lower head 12 there is a cutter expanding sleeve 50 which has a 105 frustro conical head 51 pressed upwardly by a spring 52 against extensions 53 which are provided on the lower ends of cutter carriers 35. The function of this sleeve and conical head, operated by the rather light 110 spring 52, is merely to press the cutter carrier outwardly against the wall of the drill hole to insure sufficient contact of the cutters with the wall to retard rotation of the cutters and the reamer body sufficiently to give positive expanding action when the mandrel is rotated. However, because in the average case the cutters and also the cutter carriers are in more or less forcible engagement with the wall of the hole when the tool is let down 115 to the point where reaming operations are to begin, it may not be necessary to use the cutter expanding sleeve and head.

For the particular design here shown, as I have said before, cam members 32 are arranged in three sets, each set in this particular instance comprising a vertical row of four vertically spaced cam members 32. These cam members are so vertically spaced, as shown in the various views, that in the posi- 120 125 130

tion of Fig. 2 and Fig. 5 the cam members are in horizontal planes corresponding to the horizontal planes of the carrier arms 40; so that when the mandrel and the cam members are rotated from the position of Figs. 2 and 3 to the position of Figs. 5 and 6, the cam members are moved around directly behind the several carrier arms and, in these last positions, directly support the outer 10 swinging ends of the carrier arms. This action takes place with the mandrel and the cam members in their lowermost positions, the downward movement of the mandrel being limited by the engagement of collar 55 15 with the upper surface of upper head 11, or with an intermediate collar 56 which is placed above head 11.

In the positions shown in Figs. 2 and 3 the cutter carriers are in their innermost positions and the cutters are retracted toward the center of the tool. By relative rotation of the mandrel right-handedly, looking down upon the tool, cam members 32 are thrown from the position of Fig. 3 to the position 25 of Fig. 6. During this rotation the inwardly extending noses 40^a of the carrier arms ride the cam faces 32^a and are pressed outwardly; and as the cam members come finally to the position of Fig. 6, the noses of the cams 30 move into the notches 40^b of the carrier arms, so that the parts then interengage and interlock in the position of Fig. 6. It will be noted that the notches 40^b are so formed that the cams cannot be rotated further in a right-handed direction, the cam noses coming up 35 against the walls of the notches, and the cutter carriers being prevented from swinging further outwardly by reason of engagement of their lower ends at 58 with upstanding flanges 59 on the lower body head 12. Thus, upon continued right handed rotation of the mandrel the cutter carriers are locked in their protracted or expanded positions and the mandrel and cutter carriers and body are all 40 rotatively locked together. And it will be noted also that the carrier notches 40^b are so formed that inward thrust which would tend to swing the cutter carriers about their axis pins 36 cannot force the cams back in a left-handed direction and away from the cutter carriers. Consequently in this described position of the parts, all of the parts are effectively locked against relative movement 50 by any stresses imposed upon them.

When it is desired to withdraw the reamer from the hole and up through the well pipe P backward (left-handed) rotation of the drill stem is not necessary in order to contract the cutters. It is only necessary to pull the reamer up until either the cutter carriers or the uppermost cutters come into contact with the lower edge of the pipe. Further upward movement of the drill stem will then cause upward movement of the mandrel with relation to the body and cutter carriers, com-

pressing spring 27 and moving the mandrel and its cam members up to the relative elevated position shown in Fig. 7. Spring 27 is strong enough that it will normally support the weight of the whole tool and of the drill 70 bit attached to its lower end and always keep the parts in the relative vertical position shown in Fig. 2 while drilling and reaming are in progress; but the spring may be compressed by pulling the tool up against the 75 lower end of the casing. When this occurs the cam members 32 are moved directly upwardly from their positions shown in Figs. 5 and 6, until they occupy the relative elevated positions shown in Figs. 7 and 8 or a little 80 higher than shown there; the cam members being then above their respective carrier arms and registering with the spaces between carrier arms, which spaces are at least of as great 85 vertical width as the cam members. The cam members having assumed this position then further upward movement of the mandrel, and upward movement of the body and carriers with it will cause the carriers to swing inwardly by reason of engagement of their 90 upper beveled edges 35^a with the lower end of the casing. These upper beveled edges or corners 35^a extend along a considerable length of the uppermost curved carrier arms 40 as is best shown in Fig. 1, so that a curved beveled 95 edge of some length is presented to the lower end of the casing, giving good and smooth contact with the casing or its shoe and precluding any liability of the carriers cutting into the casing and causing any binding by 100 reason of edge to edge engagement. The carriers are thus moved inwardly, their arms moving inwardly intermediate the spaced cam members 32 until the carriers and cutters are contracted sufficiently to pass with- 105 in the casing, as shown in Fig. 7. Then the spring 27 moves the parts relatively so that the cam members are moved down with a fairly heavy pressure against and upon the upper faces of the carrier arms, as shown in 110 the position of Figs. 7 and 8. The whole pressure of spring 27 is exerted in pressing the cam members down on the carrier arms and thus the carrier arms are held or locked in their inward contracted position for move- 115 ment through the pipe. Although of course the carrier arms could be moved outwardly by a sufficient force, there is no such force applied to them while being moved through the pipe. In fact if any force is applied to 120 the carrier arms during such movement it will be an inward force due to the cutters or carriers coming in contact with some locally smaller or inwardly deformed part of the pipe, which would do nothing but force the 125 carriers inwardly a corresponding distance; and the carriers would then stay in that inward position and out of normal contact with the pipe.

When the tool reaches the surface it may, 130

if desired, be subsequently put back through the pipe in the condition shown in Figs. 6 and 7. In this condition the carriers and cutters are still locked against pressing outwardly against the pipe. If reinserted in the well 5 in this condition then when the tool reaches the place where reaming operations are to begin and the cutters are again in contact with the formation, relative right handed rotation of the mandrel and cams will move the cams 10 first from the position shown in Fig. 8 to the position shown in Fig. 9. In the specific design herein shown the cams in this movement will contact somewhat with the roller cutters 41 and temporarily move the cutters 15 and carriers outwardly while the cams pass the cutters to reach the position of Fig. 9; but that temporary outward movement is of no significance. When the parts reach the 20 relative positions of Fig. 9 the cams are still resting upon the carrier arms 40 and the arms and cutters are thus locked against outward or expansive movement. And the parts may be, if desired, put into the position of Fig. 9 25 before the reamer is lowered through the casing. In any case, right handed rotation of the mandrel from the position of Fig. 9 will, as apparent from an inspection of that figure, immediately move the cam members to the 30 position of Fig. 3, the cam members then being out of engagement with the cam arms, and spring 27 will then immediately move the mandrel and the cam members relatively downwardly to the relative position of Fig. 35 2, the carriers and cutters being still contracted. And it may be noted that the parts may be, if desired, put into this last mentioned relative position before being lowered through the casing. In this position of Fig. 40 3 the carriers and cutters are not locked against outward expansive movement but are free to swing outwardly, or are moved outwardly under the light pressure of expanding spring 52, if that spring is used. However, even in the last mentioned positions of 45 the parts, and particularly if spring 52 is not used, the cutters will not forcibly ride the pipe on the way down. There is no spring action, or at least no heavy spring action, acting 50 in any one of the three collapsed positions of the parts, to force the cutters outwardly and expand them, as is the case in any usual underreamer.

In the average underreamer, where a spring 55 is used, that spring has a constant tendency to expand the cutters, and usually by a wedging action which, if anything, is enhanced by the relatively upward drag of the cutters on the pipe as the tool is lowered through the 60 pipe. But in my reamer the only function of the spring is to hold the parts in what may be termed their normal relative position of longitudinal movement and to provide that force which locks the cutters against expansion when they are in their contracted posi-

tions. It is not the spring which tends to expand the cutters.

From what has been said it will now be readily understood how the reamer, when it is put down through the pipe in any one of its contracted positions, is thrown to its expanded position by positive right-handed rotation of the drill stem, and without the use of any relative longitudinal movement; and how the cutters are contracted by the positive relative longitudinal movement caused by drawing the tool up against the lower end of the casing, and how when the cutters are thus contracted there is no force tending to make them press heavily against the pipe; and how the cutters are in fact locked against outward movement to press against the pipe wall. 75

I have described the present embodiment of my invention as an underreamer; but the invention is applicable to expansive and contractive tools used for other purposes. In fact the invention may be applied to any expansive and contractive tool in which the operations of expansion and contraction, as herein described, are applicable or desirable. 80 For instance, the invention is particularly applicable to pipe or casing perforators or cutting off tools, and needs no further description to show how my expanding and contracting mechanism is peculiarly useful as applied to devices for perforating or for cutting off a well casing. For either of such operations, only the substitution of suitable perforating or cutter carriers is necessary; and the tool, after having been lowered to the desired point in a casing, will, upon right handed rotation, immediately expand its cutters into forcible engagement with the casing, perform the desired service by virtue of continued rotation, and then be collapsed by 95 merely being pulled upwardly. 100

My invention is thus not limited to use in any specified tool, neither is it limited by the specifically described details of structure and operation as set forth in the foregoing specification for purposes of clarity of description; but on the other hand it is only to be limited as expressed in the following claims, which are to be construed in their broad and inclusive senses as well as in their restricted 110 senses as literally expressed. 115

Although, for purposes of description, I have described the mandrel as being longitudinally movable within the body, without or with relation to the body, it is understood 120 that this mode of description of the mechanism has been adopted only for simplicity of description of the various relative movements of the parts. The various operations all take place by reason of relative movements between the mandrel and cutter-carriers—relative rotative movements and relative longitudinal movements. As regards the relative rotative movements, especially when the tool 125 is in the hole, those rotative movements may 130

very properly be visualized as rotation of the mandrel within the body and cutters. For rotation in resetting the tool at the top of the hole, the body and cutters may either be held 5 from rotation while the mandrel is rotated within them, or the body and cutters may be relatively rotated about the mandrel to effect the same result.

In the relative longitudinal movements between the mandrel and cutters, however, it is only proper to view that movement as being a mandrel movement in the operation of collapsing the cutters—that is, when the mandrel is moved upwardly relative to the cutters so that the cutters then drop inwardly under the mandrel cams. And even in that case, it is proper to view that relative movement as a downward movement of the cutters on the mandrel rather than an upward movement of the mandrel with relation to the cutters. The view that the mandrel moves up between the cutters has, in this specification and the following claims, been largely adopted because of the fact, in the specific embodiment of the invention herein described, that relative longitudinal movement is the movement that contracts the cutters. In the following relative upward movement of the cutters with relation to the mandrel, which is caused by the spring 27, it is more proper to view that relative movement as being an upward relative movement of the cutters on the mandrel, rather than the downward movement of the mandrel between the cutters. 35 The mandrel is mounted upon the drill stem and the spring cannot move the mandrel and drill stem, but can only move the body and cutters.

I claim:

40 1. In an expanding tool of the character described, the combination of a body, a cutter carrier mounted on the body to move laterally thereof, a mandrel in the body movable both rotatively and longitudinally with relation to the cutter carrier, and a cam on the mandrel adapted to engage and move the cutter carrier by virtue of rotation and to be moved out of engagement with the cutter carrier by virtue of relative longitudinal movement.

50 2. In an expanding tool of the character described, the combination of a body, a cutter carrier mounted on the body to move laterally thereof, and a mandrel mounted in the body for longitudinal movement along and rotative movement about the longitudinal axis, and a cam on the mandrel adapted to engage and operate the cutter carrier in one longitudinal position of the mandrel and to be out of engagement with the carrier in another longitudinal position of the mandrel.

60 3. In an expanding tool of the character described, the combination of a body, a cutter carrier mounted on the body to move laterally thereof, a rotary and longitudinally mov-

able mandrel within the body, a cutter carrier operating cam on the mandrel located behind the cutter carrier in one longitudinal position of the mandrel and cam and located out of register with the cutter carrier in another longitudinal position of the cam. 70

4. In an expanding tool of the character described, the combination of a body, a cutter carrier mounted on the body to move laterally thereof, a rotative and longitudinally movable mandrel within the body, a cam on the mandrel adapted by rotation when in one longitudinal position to engage the inner face of the cutter carrier and move the cutter carrier outwardly, stop means on the cutter carrier limiting such rotative movement of the cam to the position in which the cutter carrier is moved outwardly, and the cam being movable out of engagement with the cutter carrier by longitudinal movement of the mandrel and cam. 80

5. In an expanding tool of the character described, the combination of a body, a cutter carrier mounted on the body to move laterally thereof, a rotative and longitudinally movable mandrel within the body, a cam on the mandrel adapted by rotation when in one longitudinal position to engage the inner face of the cutter carrier and move the cutter carrier outwardly, stop means on the cutter carrier limiting such rotative movement of the cam to the position in which the cutter carrier is moved outwardly, and the cam being movable out of engagement with the cutter carrier by longitudinal movement of the mandrel and cam, the cutter carrier being movable inwardly when the cam is so moved longitudinally, and a spring tending to move the mandrel longitudinally to engage the cam endwise against the cutter carrier to hold it in its inward position. 95

6. In an expanding tool of the character described, the combination of a body, a cutter carrier mounted on the body to move laterally thereof, a rotative and longitudinally movable means adapted by rotative movement to move the cutter carrier outwardly and adapted by longitudinal movement to engage the cutter carrier to hold it in inward position. 110

7. In an expanding tool of the character described, the combination of a body, a cutter carrier mounted on the body to move laterally thereof, a mandrel in the body rotatable about and movable along a longitudinal axis between two positions, a cam on the mandrel located behind the cutter carrier in one of said longitudinal positions of the mandrel and adapted in that position to move the carrier out by virtue of mandrel and cam rotation, stop means on the carrier limiting rotative movement of the cam to its position in which it moves the carrier out, the cam being movable longitudinally with the mandrel to move out of engagement with the car- 120
125
130

rier and its stop means for further rotative movement out of engagement with the carrier, and a spring acting between the cutter carrier and the mandrel to cause movement 5 of the parts back to their first mentioned relative longitudinal positions when the cam is rotated out of engagement with the carrier.

8. In an expanding tool of the character described, the combination of a body adapted 10 to be rotated about a vertical axis, a mandrel mounted in the body for rotation relative thereto about a vertical axis and also for movement vertically with relation to the body between a lower position and an upper 15 position, a cutter carrier on the body and movable horizontally with relation thereto, and a carrier operating cam on the mandrel positioned in the horizontal plane of the carrier when the mandrel is in its lower position 20 and adapted to be raised above the carrier when the mandrel is moved to its upper position.

9. In an expanding tool of the character described, the combination of a body adapted 25 to be rotated about a vertical axis, a mandrel mounted in the body for rotation relative thereto about a vertical axis and also for movement vertically with relation to the body between a lower position and an upper 30 position, a cutter carrier on the body and movable horizontally with relation thereto, and a carrier operating cam on the mandrel positioned in the horizontal plane of the carrier when the mandrel is in its lower position 35 and adapted to be raised above the carrier when the mandrel is moved to its upper position, the carrier being movable to a position under the cam when the cam is in its upper position.

40 10. In an expanding tool of the character described, the combination of a body adapted to be rotated about a vertical axis, a mandrel mounted in the body for rotation relative thereto about a vertical axis and also for movement vertically with relation to the body between a lower position and an upper 45 position, a cutter carrier on the body and movable horizontally with relation thereto, and a carrier operating cam on the mandrel positioned in the horizontal plane of the carrier when the mandrel is in its lower position 50 and adapted to be raised above the carrier when the mandrel is moved to its upper position, the carrier being movable to a position under the cam when the cam is in its upper 55 position, and a spring acting on the mandrel to move the cam forcibly downwardly upon the carrier when it is in position under the cam.

60 11. In an expanding tool of the character described, the combination of a body, a cutter carrier mounted on the body to move laterally thereof, said cutter carrier having a plurality of longitudinally spaced recesses 65 in its inner face, and carrier operating means

comprising a series of longitudinally spaced cams rotatable on a longitudinal axis and also movable longitudinally of the body and adapted in one longitudinal position to enter 70 said spaced recesses.

12. In an expanding tool of the character described, the combination of a body rotatable about a central vertical axis, a swinging cutter carrier mounted at one edge on a vertical axis on the body and having its free 75 end adapted to swing inwardly and outwardly to and from the body, and a cam member within the body rotatable about and movable vertically along a vertical axis and adapted in one vertical position to engage 80 and move the swinging carrier and in another vertical position to be out of engagement with the swinging carrier.

13. In an expanding tool of the character described, the combination of a body rotatable about a central vertical axis, a swinging cutter carrier mounted at one edge on a vertical axis on the body and having its free end adapted to swing inwardly and outwardly to and from the body, said swinging 85 carrier having on its inner face toward the body a series of vertically spaced recesses, a mandrel mounted in the body and rotatable about and movable vertically along the axis of the body, and a series of vertically 90 spaced cams on the mandrel whose spacing corresponds with the spacing of said recesses.

14. In an expanding tool of the character described, the combination of a body rotatable about a central vertical axis, a swinging cutter carrier mounted at one edge on a vertical axis on the body and having its free end adapted to swing inwardly and outwardly to and from the body, the swinging 100 end of said carrier being divided into a plurality of vertically spaced fingers, cutters carried at the swinging end of the carrier in the spaces between fingers, a mandrel in the body rotatable upon and vertically movable along the axis of the body, a spring tending to move the mandrel downwardly relative to the body, and a series of vertically spaced cam members on the mandrel and whose vertical spacing corresponds to the 105 vertical spacing of said carrier fingers, so that in one vertical position of the mandrel the cam members are in horizontal registration with said fingers and in another position of the mandrel said cam members are 110 in horizontal registration with the spaces between said fingers.

15. In an expanding tool of the character described, the combination of a body, a cutter carrier mounted on the body to move laterally thereof, a rotatable cam mounted in the body and adapted to engage the carrier and move it laterally outwardly away from the body, the carrier having a cam receiving notch into which the cam enters, said notch 115 120 125 130

engagement with the cam serving to prevent further rotation of the cam and to prevent backward cam rotation by virtue of inward pressure exerted upon said carrier.

5 16. In an expanding tool of the character described, a mandrel adapted for attachment to a drill stem, a cutter carrying cage, a cutter carrier in the cage and movable in and out to and from the mandrel, the cutter carrier being movable longitudinally with relation to the mandrel and the mandrel being rotative with relation to the carrier, and a cam on the mandrel adapted to engage the carrier in one longitudinal position and to be out of such engagement in another longitudinal position.

10 17. In an expanding tool of the character described, a mandrel adapted for attachment to a drill stem, a cutter carrying cage, a cutter carrier in the cage and movable in and out to and from the mandrel, the cutter carrier being movable longitudinally with relation to the mandrel and the mandrel being rotative with relation to the carrier, a cam on the mandrel adapted to engage the carrier in one longitudinal position and to be out of such engagement in another longitudinal position, and yielding means to move the cutter longitudinally with relation to the mandrel.

15 18. In an expanding tool of the character described, a mandrel adapted for attachment to a drill stem, a cutter carrying cage, a cutter carrier in the cage and movable in and out to and from the mandrel, the cutter carrier being movable longitudinally with relation to the mandrel and the mandrel being rotative with relation to the carrier, a cam on the mandrel adapted to engage the carrier in one longitudinal position and to be out of such engagement in another longitudinal position, and stop means on the carrier adapted to limit relative rotation of the cam when the cutters are in their relative longitudinal position for cam engagement.

20 19. In an expanding tool of the character described, a mandrel adapted for attachment to a drill stem, a cutter carrying cage, a cutter carrier mounted on the cage and movable in and out to and from the mandrel, the cutter carrier being movable longitudinally with relation to the mandrel and the mandrel being rotative with relation to the carrier, the mandrel having a formation adapted by rotative movement to move the carrier outwardly and adapted by longitudinal movement to engage the carrier and hold it in inward position.

25 20. In an expanding tool of the character described, a mandrel adapted for attachment to a drill stem, a cutter carrying cage, a cutter carrier mounted on the cage and movable in and out to and from the mandrel, the cutter carrier being movable longitudinally with relation to the mandrel and the mandrel being rotative with relation to the carrier,

the mandrel having a longitudinally facing shoulder adapted to be selectively moved into and out of carrier engaging position by relative rotation.

21. In an expanding tool of the character described, a mandrel adapted for attachment to a drill stem, a cutter carrying cage, a cutter carrier mounted on the cage and movable in and out to and from the mandrel, the cutter carrier being movable longitudinally with relation to the mandrel and the mandrel being rotative with relation to the carrier, the mandrel having a longitudinally facing shoulder adapted to be selectively moved into and out of carrier engaging position by relative rotation, and yielding means moving the carrier longitudinally relative to the mandrel in a direction to move the carrier against said shoulder.

22. In an underreamer, a cage, a cutter carrier mounted in the cage and movable in and out, a mandrel extending through said cage and mounted for rotary movement relative thereto, said mandrel being provided with eccentric shoulders for engagement with the inner edge of the cutter carrier, and a shoulder formed on said mandrel beneath which the carrier is adapted to engage when in its inward retracted position.

23. In an underreamer, a cage, a cutter carrier mounted in the cage and movable in and out, a mandrel extending through said cage and mounted for rotary movement relative thereto, said mandrel being provided with eccentric shoulders for engagement with the inner edge of the cutter carrier, a downwardly facing shoulder formed on said mandrel beneath which the cutter carrier is adapted to engage when in inward retracted position, and yielding pressure means for normally exerting upward pressure against said carrier.

24. In an underreamer, a cutter carrying cage, a cutter carrier mounted in the cage and arranged to move in and out therein, a mandrel associated with said cage, the cutter carrier being also movable vertically longitudinally with the reference to said mandrel, an eccentric face formed on said mandrel for engagement with the inner edge of said carrier, and means on said mandrel and carrier for locking the latter against vertical longitudinal movement when in its inner retracted position.

25. In an underreamer, a cutter carrying cage, a cutter carrier mounted in the cage and arranged to move in and out therein, a mandrel associated with said cage, the cutter carrier being also movable vertically longitudinally with reference to said mandrel, an eccentric face formed on said mandrel for engagement with the inner edge of said carrier, means on said mandrel and carrier for locking the latter against vertical longitudinal

movement when in its inner retracted position, and yielding pressure means arranged within said cage beneath said carrier.

26. In an underreamer, a cutter carrying cage, a cutter carrier mounted in the cage and movable inwardly and outwardly therein, a mandrel extending into said cage and arranged to rotate therein, the cutter-carrier being also movable longitudinally with relation to said mandrel, means on said mandrel for engaging and projecting the cutter carrier when said mandrel is rotated, and means on said mandrel and carrier for locking the latter in its inward retracted position.

15 27. In an underreamer, a cutter carrying cage, a cutter carrier mounted in the cage and movable inwardly and outwardly therein, a mandrel extending into said cage and arranged to rotate therein, the cutter-carrier being also movable longitudinally with relation to said mandrel, and means on said mandrel and carrier whereby the latter is projected upon relative rotary movement of said mandrel and whereby said carrier is locked 20 against vertical longitudinal movement when retracted.

25 28. In an expanding tool of the character described, a mandrel adapted for attachment to a drill stem, a cutter carrying cage, a cutter carrier mounted on the cage and movable in and out to and from the mandrel, the cutter

carrier being movable longitudinally with relation to the mandrel and the mandrel being rotative with relation to the carrier, the mandrel having a formation adapted to move the carrier outwardly by virtue of relative movement between the mandrel and carrier, and the mandrel also having a longitudinal facing shoulder adapted to be selectively moved into and out of carrier engaging position by relative rotation.

29. In an expanding tool of the character described, the combination of a cutter carrying body, a cutter carrier mounted on the body to move laterally thereof, a rotatable cam mounted in the body and adapted by rotation relative to the carrier to move the carrier outwardly, and yielding means tending to move the carrier outwardly.

30. In an expanding tool of the character described, the combination of a cutter carrying body, a cutter carrier mounted on the body to move laterally thereof, a rotatable cam mounted in the body and adapted by rotation relative to the carrier to move the carrier outwardly, and yielding means independent of the cam acting to move the carrier outwardly.

In witness that I claim the foregoing I have hereunto subscribed my name this 17th day 50 of January, 1928.

LAWRENCE S. CAMPBELL.
